United States Patent

Des. 237,906

Patented Dec. 2, 1975

237,906

PRINTER CABINET

Arthur A. Hagstrom, Hoffman Estates, and Hans K. Keipert, Glenview, Ill., assignors to Teletype Corporation, Skokie, Ill.

Filed Oct. 4, 1974, Ser. No. 512,289

Term of patent 14 years

Int. Cl. D14—02; D18—02
U.S. Cl. D64—11 R

FIG. 2

FIG. 3

FIG. 4

FIG. 5

FIG. 1 is a front left perspective view of a printer cabinet, showing our new design;

FIG. 2 is a top plan view thereof;

FIG. 3 is a right side elevational view thereof;

FIG. 4 is a front elevational view thereof; and

FIG. 5 is a rear elevational view thereof.

We claim:

The ornamental design for a printer cabinet, substantially as shown.
